UNITED STATES PATENT OFFICE.

MARIUS RATIGNIER, OF VILLEURBANNE, RHONE, FRANCE.

CONTINUOUSLY-OPERATING MACHINE FOR PHOSPHATING AND WASHING FABRICS.

Application filed September 4, 1926, Serial No. 133,586, and in France September 19, 1925.

This invention relates to a continuously operating machine for phosphating and washing fabrics, or for immersing fabrics freely for a variable time in a succession 5 of different baths.

In order to preserve the particular appearance of certain fabrics; crêpe de chine, for example; they must be submitted to a succession of washing operations and immersed 10 in a phosphating bath, where they should be able to contract freely. This treatment actually necessitates an important hand operation and voluminous apparatus.

The object of the present invention is to 15 provide a continuously operating machine carrying out mechanically the different operations of washing and phosphating, and thus permitting an increased manufacturing yield with a decreased hand operation 20 and material of small bulk.

The machine under consideration is essentially formed with a central drum immersed in a phosphating bath and having an intermittent or differential movement, obtained by means of an endless cloth, which holds between itself and the periphery of the drum the folds of fabric given out at 25 constant speed and previously washed by ramps formed around the periphery of a leading drum, the cloth being finally washed 30 by successive immersions in a reservoir having a double compartment.

The annexed drawing shows, by way of example, one practical embodiment of the invention.

On the drawing:—

Fig. 1 is a longitudinal view of the whole machine:

Fig. 2 is a plan; and

Fig. 3 shows the details of the control mechanism for the phosphating bath.

Figure 4 is an enlarged sectional view of the central drum and accessories.

Referring to the drawing:—

The machine comprises a distributing roller *a*, a curved spreading tube *b*, followed by a second cylinder *c*, beneath which are disposed two ramps *c'*, and a drum whose periphery is formed by bars *d*. This drum 45 is mounted loosely on its shaft, and around it are arranged concentric ramps *e*, projecting hard water. Above the drum are fixed two washing ramps *e'*, fed by soft water, and between which the fabric to be treated 50 passes. Above these ramps is mounted a cylinder *f*, followed by two rollers *h*, *h'*, forced

against each other by a counterweight *h''*. The frame of the machine also supports a phosphate bath *i* in which is arranged a drum formed with a cloth *i'* stretched 60 on to concentric bars *i''*. This drum is driven by an endless cloth *k* mounted on cylinders *k¹*, *k²*, *k³*, *k⁴*, *k⁵*, *k⁶*, and controlled by means of two chains, fixed to its edges, through toothed wheels. Above the cylinder 65 *k'* is disposed a roller *l*, and a perforated tube *l'* serving to project the phosphated solution. On the roller *l* are formed circular grooves in which combs, or any other device which will ensure the taking off of the fabric, engage. Between the two rollers *l* and *k⁶*, is mounted a curved spreading tube *l''*, followed by two rollers *m*, *m'* pressed against each other by a counterweight *m''*. The frame also supports a washing vat *n* with 70 two compartments, provided at its bottom part with transversal rollers *n'*, arranged below other rollers *n''* disposed above the vat.

At the outlet of the vat are disposed two 80 washing tubes *n²* which are followed by two cylinders *o*, *o²* arranged above a trough *r* containing acid liquid and comprising a bottom roller *r'* and a top roller *r''* followed by a stretching cylinder *r²*. As shown in Fig. 85 3, the rotation of the cylinder *k⁵* drawing the endless cloth *k* is controlled by the aid of a roller *s* operated alternatively by a lever *t* driven by an eccentric *u* mounted on the shaft of a roller *m'*, the slight rotation of the cam being controlled by gears *u'*, *u''*, *v* and *v'*. The pressing cylinders and the driving of the machine are operated by a series of bevel wheels shown in Fig. 2.

As is easy to understand from Fig. 1, the fabric *z* led from the cylinder *a* is spread out by the curved tube *b* on to the second cylinder *c* and passes over the drum where it is sprinkled by the ramps *c'* and *e* projecting hard water. Leaving the drum the fabric is washed by the two ramps *e'* projecting soft water. The fabric is then rolled over the cylinder *l* where it is drawn at a constant speed and from which it is 90 disengaged by the combs *l²*.

In consequence of the intermittent movement of the drum *i'* communicated thereto by the driving of the endless cloth *k*, the fabric fed by the rollers *h* and *l* simultaneously driven by beveled gears as shown in 95 Figure 2 is disposed in folds on the periphery of the drum when the latter is sta-

tionary. The successive displacements of the drum thus determine a series of superposed folds z' , which are maintained between the endless-cloth k and the drum i' . There results a free immersion in the phosphating bath whose duration is proportional to the speed of the drum i . By modifying the ratio of the gears for the cam movement, it is possible to vary at will the speed of the drum i .

10 The fabric z previously sprinkled by the perforated tube l' , which projects a phosphated solution, passes from the exit of the vat i on to the spreading tube l'' so as to be pressed between the rollers m, m' , and drawn 15 into the washing bath constituted by the two compartments of the vat n . On leaving the latter, the fabric is rinsed by the two perforated tubes n^2 and then plunged into the acid bath of the reservoir r , after which it is 20 folded so as to be ready to undergo fresh operations.

It will be understood that the machine is also applicable to all dyeing operations, it can comprise any desired number of baths, 25 provided with intermittently moving drums, the speed of which can be proportioned to the time necessary for the penetration of the products.

The phosphating drum can also turn continuously at a uniform speed less than that of the fabric, which is thus retained in folds around the periphery of the drum.

I claim:

1. In a continuously operating machine for washing and phosphating fabrics, the combination of means for leading the fabric into the machine at a constant speed, means for projecting different liquids on to the fabric as it passes through the machine, 35 baths adapted to contain various liquids in which the fabric is immersed as it passes through the machine, means for pressing out the liquid from the fabric after its immersion or projection of liquid thereon, rotary means 40 for immersing the fabric in one of said baths, and means for actuating the rotary means with an intermittent movement, so that the fabric is disposed on the rotary means in a series of superposed folds when 45 the rotary means is stationary and as the fabric passes through the said bath.

2. In a continuously operating machine for phosphating and washing fabrics, the combination of means for leading the fabric 55 into the machine at a constant speed, means for projecting different liquids on to the fabric as it passes through the machine, baths adapted to contain liquids in which the fabric is immersed as it passes through 60 the machine, means for pressing out the liquid after its immersion or projection of liquid thereon, rotary means for immersing said fabric in one of said baths, means for operating the rotary means, and means for 65 actuating said operating means with an in-

termittent movement, so that the fabric is disposed in a succession of superposed folds on the rotary means when the latter is stationary and during its immersion in said bath.

3. A continuously operating machine for phosphating and washing fabrics, comprising, in combination, means for leading the fabric into the machine at a constant speed, means for projecting liquid on to the fabric, means for pressing out the liquid from said fabric after liquid projection thereon, a bath adapted to contain a phosphating liquid, rotary means around which the fabric passes through said bath, means for driving 80 said rotary means, means for actuating the driving means with an intermittent movement, so that the fabric is disposed in a succession of superposed folds on said rotary means when the latter is stationary, means 85 wherein the fabric is washed after its passage through the bath, means for causing the fabric to undergo a succession of immersions in said washing means, means containing acidulated liquid, and means for immersing 90 said fabric in said liquid after the washing operation.

4. A continuously operating machine for phosphating and washing fabrics, comprising, in combination, a drum wherefrom the 95 fabric is drawn into the machine at a constant speed, means for projecting water on to the fabric at successive intervals, means for pressing out the water after the projection thereof on to the fabric, a bath adapted 100 to contain a phosphating liquid, a drum rotatably arranged therein, means for rotating said drum, means for driving said last mentioned means with an intermittent movement so that the fabric is disposed on 105 the periphery of the drum in a series of superposed folds when the latter is stationary, means for pressing the fabric after it leaves the bath, a washing vat, means for subjecting the fabric to a succession of immersions in said vat, a second bath adapted 110 to contain acidulated liquid, means for causing the fabric to pass through said second bath, and means for stretching and folding the fabric after its passage through the latter.

5. A continuously operating machine for phosphating and washing fabrics, comprising, in combination, a drum wherefrom the 115 fabric is led at a constant speed, means for 120 projecting a liquid on to the fabric, rotary means for causing the fabric to pass in close proximity to the projecting means, means for again projecting a liquid on to the fabric after the latter leaves the rotary means, means for pressing the fabric, means for 125 projecting a treating solution on to the fabric, a bath adapted to contain a phosphating liquid, a drum rotatably arranged therein, means for rotating said drum, 130

means for driving said last mentioned means with an intermittent movement, so that the fabric is disposed on the periphery of the drum in a series of superposed folds when the drum is stationary, means for pressing the fabric after it leaves the said bath, a washing vat, means for subjecting the fabric to a succession of immersions in said vat, a second bath adapted to contain acidulated liquid, means for causing the fabric to pass through said second bath, and means for stretching and folding the fabric after its passage through the latter.

6. A continuously operating machine for washing and phosphating fabrics, comprising in combination, means for leading the fabric into the machine at a constant speed, means for projecting a liquid on to the fabric, means for pressing out the liquid

from said fabric after the projection thereof, a bath adapted to contain a treating solution, a drum rotatably arranged in said bath, an endless cloth passing around the drum and adapted to rotate the drum and to cause the fabric to pass between said cloth and drum, means for driving said cloth with an intermittent movement, so that the fabric is arranged in a series of superposed folds between said cloth and the drum when the latter is stationary, means wherein the fabric is washed after its passage through the phosphating bath, means for causing the fabric to undergo a succession of immersions in said washing means, means adapted to contain acidulated liquid, and means for immersing the fabric in said liquid after the washing operation.

MARIUS RATIGNIER.
